BLOW OPEN, BLOW CLOSED CIRCUIT
BREAKER SYSTEM

Joseph D. Wood, Strafford Village, Pa., assignor
to I-T-E Circuit Breaker Company, Philadelphia, Pa., a corporation of Pennsylvania

Original application March 16, 1948, Serial No. 15,183. Divided and this application October 27, 1948, Serial No. 56,755

9 Claims. (Cl. 200—97)

1

This application is a division of my application Serial No. 15,183, filed March 16, 1948 now abandoned.

My invention relates to a novel sequential trip system, and more particularly relates to a sequential trip system in which circuit breakers have time differentials from each other of the order of cycles in response to short circuit current conditions and have time differentials from each other of the order of seconds in response to overload fault conditions in the circuit being protected.

In such systems it is desirable that the contacts of the circuit breakers be so constructed that normally during the closing operation of the breaker it be supplied with a "blow-closed" effect, i. e., to have the magnetic fields induced by the currents in the controlled circuit tend to drive the contacts closed. This ensures good contact on closing and is especially desirable where breakers may be closed against excessive currents or short circuit conditions.

Under such circumstances, the contacts are sufficiently closed to enable relatching of the contacts before tripping occurs in response to such short circuit conditions and thus avoids chattering or freezing at the contacts due to poor contact engagement during closing.

While it is thus desirable to have a "blow-closed" effect during closing in order to ensure complete latching in response to the fault currents, it is at the same time desirable to retain the effect of a "blow-open" action during the tripping of the breaker, i. e., an action in which when the breaker is tripped in response to a fault current, the electromagnetic fields set up by such currents function in a direction to assist in driving the contacts to disengagement.

In accordance with my novel sequential trip system, I accordingly provide circuit breakers in such a system having time delays both for short periods of the order of cycles for currents up to 1.C and long periods of the order of seconds for overloads which are individual to each of the breakers and differ from each other in the short circuit current ranges by cycles of separation and in the long current by seconds of separation and which are provided with what I above define as a "blow-closed," "blow-open" action.

Accordingly, an object of my invention is to provide a novel sequential trip mechanism in which the breakers are each provided with "blow-closed, blow-open" mechanisms.

Another object of my invention is to provide a novel sequential trip system in which each of

2

the circuit breakers is constructed so that the electromagnetic fields set up assist with the circuit breaker in closing and also assist in the opening of the contacts in response to fault currents.

The foregoing and many other objects of my invention will become apparent from the detailed description of the figures which follows, in which

Figure 1 is a schematic illustration of one form of circuit breaker which may be employed in my novel sequential trip system.

Figure 2 is a circuit diagram of a system in which said circuit breakers may be used.

Figure 3 are curves showing the time current responses of circuit breakers employed in my system.

Figure 4 is a schematic illustration of another form of breaker which may be used in my system showing the breaker in closed position.

Figure 4a is a schematic illustration of the distribution of forces.

Figure 5 shows the same breaker in full open position.

Figure 6 shows the breaker in pre-set position ready to be reclosed.

Referring now to the figures, I have here shown my novel circuit breaker 10 which is so arranged that during the closing movement and just as the contacts engage, but before they have fully engaged, the current loop through the elements provides a blow-closed effect. When the circuit-breaker is tripped, the elements are so arranged that the current loop provides a blow-open effect.

The circuit breaker 10 is supported in any suitable manner on a back panel 11, carrying additional supporting brackets, not shown, to support the various pivot pins hereinafter described.

The back panel 11 carries an upper back connection stud 15 and a lower back connection stud 16, mounted in any suitable insulators 115 and 116. The upper back connection stud 15 carries at the end thereof a stationary contact structure 17. Movable contact arm 25 carrying movable contact 26 and arc horn 27 is pivotally mounted on the pin 28 which passes through the arcuate horizontally extending slot 29 in extension 31 of the lower back connection stud 16.

Further details of contact arm 25 are shown in Figure 1a of application Serial No. 720,561, filed January 7, 1947.

The current path established when the contacts are closed is thus from the upper back connection stud 15 to the stationary contact structure 17, then through movable contact 26 and

movable contact arm 25 to the extension 31 of the lower back connection stud 16 and then to the lower back connection stud 16.

It will thus be seen that when the contacts are closed, a U-shaped current loop is established with the contact elements 17-26 at one of the bends or corners of the loop.

The movable contact 25 is held closed during the operation of the circuit breaker by the toggle 52, one link 53 of which is connected to the pin 50 on contact arm 25, the opposite end of the link 53 being connected to the knee pin 55 of the toggle 52.

The other link 54 of the toggle 52 is connected at one end to the knee pin 55 and is pivoted at the other end on the stationary pin 57. Link 54 has a downward extension 62 which with link 54 forms a bell crank lever 54-62. Roller 63 secured at the end of link 62 is engaged in detent 64 of latch 65.

Trip magnet 71 is energized in accordance with current conditions in the main circuit through the current transformer 73 in the main circuit. Armature 72 of magnet 71 is connected to a short time delay device 74 and through spring 51 to a long time delay 74'. Both the long and short time delay are here shown schematically and may be as shown in Patent 2,439,165 assigned to the assignee of the present application.

When prolonged overload current conditions of the order shown in the upper portions A to D of curves 1-4 obtains, the armature is operated against the delaying action of the long time delay 74'. When a short circuit condition of the order shown in the lower portions E to H of curves 1-4 obtains, the armature is operated against the delaying action of the short time delay of device 74, all as more specifically described in the above-identified patent.

The time delay characteristics of each of the circuit breakers in the system have individual time characteristics, such as shown in curves 1-4 of Figure 3. Accordingly, as explained in the above-identified patent, only the circuit breaker nearest the fault will open.

When the overload trip coil 71 is energized over a circuit to current transformer operated by short circuit current in the main circuit protected by the circuit breaker, the armature 72 is raised against extension 67 of latch 65 causing the latch 65 to pivot counterclockwise about the stationary pin 66 so that the detent 64 thereof disengages roller 63 and the toggle 52 may break downwardly.

During the closing operation, the possible movement of the toggle upwardly through center is prevented by the cross-bar or stop 70 above the knee pin 55. When the toggle 52 has broken downwardly, thus permitting the contact 25 to be forced open by the blow-open effect, the knee pin 55 drops and roller 63 rises. Roller 63 is connected to the link 75. Link 75 is provided at its outer left-hand end with a slot 76 in which rides the pin 77. Pin 77 is connected to the upper end of the bell crank lever latch 78 which is pivoted on the pin 79.

Latch 78 has a detent 80 which engages roller 81 on the closing arm 82. Arm 82 is pivotally mounted on the pin 53 and is biased toward the right into clockwise movement by the compression spring 84.

When now the roller 63 rises up toward the left, on opening of the contacts, the link 75 is driven to the left rapidly and when the end 76a of the slot 76 strikes pin 77, latch 78 is given a

hammer blow in a counterclockwise direction to disengage the detent 80 from roller 81.

The compression spring 84 is now in a position to drive the arm 82 clockwise around the pivot 83. This results in the movement of the parts to the condition wherein the closing toggle 90 has collapsed, and in which the adjustable stop member 61 at the upper end of the arm 82 strikes the extension 62 of the link 54 rotating link 54-62 in a counterclockwise direction to re-extend the toggle 52 once more and to re-engage the roller 63 in detent 64 of latch 65.

The re-setting or extending of the toggle 52 does not at this time, however, result in closing of the circuit breaker, since pin 85 on arm 82 which is connected to arm 61 moves the arm 61 to the right, thus moving the pin 60 at the lower end of contact arm 25 to the right. This moves the pin 28 of the contact arm 25 to the right-hand side of the slot 29 but at the same time pushes the pin 60 over sufficiently so that the contact arm continues to rotate outwardly toward the left around pin 28 which is held by the right-hand end of slot 29. Thus, even though the latches are re-set, the circuit breaker remains open.

The closing toggle 90 is prevented from breaking upwardly by the stop 95. Toggle 90 comprises a link 93 connected by pin 94 to the closing arm 82 and connected at the other end to the knee pin 66. Link 97 is connected at one end to knee pin 66 and at the other end to the stationary pin 68. Closing solenoid 99 is provided with the armature 100.

Now when the circuit breaker is in the open position with the latches all re-set, the contacts may be closed by energization of the solenoid coil 99. On such energization the armature 100 is raised to extend the toggle 90. When the toggle 90 is thus extended, closing arm 82 is rotated counterclockwise to the left about pin 83. This compresses the spring 84 and moves the arm 82 over to the left until latch 78 engages roller 81 on the arm 82. At the same time the movement of arm 82 to the left pulls the arm 61 to the left, thus pulling on pin 60 and causing the contact arm 25 to rotate in a counterclockwise direction around the pivot pin 50.

Spring 84 is provided only to re-set the toggle 52 and consequently is a relatively light spring so that it does not interfere with the closing of contacts as would be the case where opening springs are used. Thus, the mechanical force needed to close the contact is only necessary to overcome the inertia of the parts and the relatively slight force of the re-setting spring 84.

The contacts are driven home once they are initially engaged by the blow-closed effect below described. In fact, the closing coil and armature, as hereinafter pointed out, are aided by the arrangement of the parts which produce a net blow-closed effect during closing.

Also, the travel which is given to the closing coil and armature 100 need merely be sufficient to complete the closing operation and no over-travel need be provided to provide any hammer blow or kinetic effect to slam the contacts home, owing to the blow closed effect described below. The parts may thus be made lighter and at the same time, owing to the utilization of the electromagnetic forces to close the contacts rather than sheer mechanical forces or kinetic energy, the parts are more durable.

The operations whereby a blow-closed effect is secured during closing and closed conditions

and a blow-open effect is secured during tripping will now be described.

In the position shown in Figure 1 with the circuit breaker closed, when a short circuit current flows through conductor 15 and the fixed and movable contacts 18 and 26 through movable contact arm 25 and back through conductor 16, a force is applied to the movable arm 25 which is transferred through pin 50 to link 53 and pin 55 to set up a force on the bell crank 54 and 62 which is in a clockwise direction about pin 57.

At this instant, the force is resisted by the latch 64 engaging pin 63 from driving the arm 75 to the left. The overload relay 71 connected in series in the circuit through conductors 15 and 16 described above is energized by this same overload current and operates its armature 72 to engage the projection 67 rocking the latching lever 65 about pin 66 in a counterclockwise direction and disengaging latch 64 from pin 63.

The above described forces thereupon are free to act and the contact arm 25 is rocked in a counterclockwise direction about the pin 60. It should be noted at this point that the blow-open effect on the arm 25 described above has a lever arm extending to the pin 69 so that although the resultant force of this blow-open effect is applied at the pin 50, it is this force at pin 50 times the lever arm formed to the pin 60 which produces the counterclockwise movement of the arm 25.

Upon disengagement of the latch 64 from pin 63, the toggle 52 collapses downwardly, rocking the bell crank arm 54 and 62 in a clockwise direction about the pin 57. The movement of the pin 63 to the left as a result of this operation operates the link 75 to the left until the pin 77 engages the right-hand end 76a of the slot 76. Further movement of the pin 63 thereupon rocks the bell crank 78 about its pivot 79 in a counterclockwise direction until the latch 80 disengages the pin 81.

Opening springs attached to movable contact arm 39 may be provided to ensure opening at no load.

When now the latch 80 disengages pin 81, the arm 82 is operated clockwise about pin 83 under the action of the compression spring 84, collapsing the toggle 90 so that the links 93 and 97 rock downwardly and the knee pin 96 is moved down to engage the armature 100 of the closing magnet 99.

A further result of the movement of arm 82 is to move the link 61 to the right. As the pin 60 of link 61 is moved to the right, the contact arm 25 is also carried to the right with the pin 28 moving in the slot 29 until the pin 28 engages the right-hand end of the slot. During this movement the toggle mechanism 52, including links 53 and 54, have been straightened out to the position shown in Figure 3 of application Serial No. 720,561, filed January 7, 1947. Movement of the link 54 operates this bell crank about pin 57 in a counterclockwise direction, thus operating the pin 63 and through it the link 75 to the right until the pin 77 is in the intermediate position of the slot 76.

At this position the latch 65 which has in the meanwhile been restored to its original position as a result of the de-energization of the magnet 71 re-engages the pin 63 to re-set the toggle mechanism 55 and hold it in the position preparatory for the re-closing operation.

On re-closing the holding magnet 99 is operated, operating its plunger armature 100 up-

wardly against the knee pin 96 and the latter is raised toward the stop 95 thus straightening out the knee toggle to the position shown in Figure 1.

During this operation the link 93 is moved to the left operating the arm 82 in a counterclockwise direction about pin 83 until the pin 81 moves over the latch 80 and re-sets itself in engagement with the latch. The movement of the arm 82 in a counterclockwise direction operates through pin 85 to move link 61 to the left. As a result, the pin 60 now rotates the arm 25 about pin 50 which is now fixed by the re-engaged toggle 52 until the contacts re-engage.

If now the contacts close on a short circuit during the instant of engagement, the magnetic forces set up by the short circuit currents will produce a magnetic action about the pin 50. The portion of the magnetic forces in the sector 41 between pin 50 and the engaging contacts would tend to drive the movable arm in a counterclockwise direction about the pin 50. At the same time the magnetic forces below the pin 50 will operate on the link extending from 60 to 50, including the section 40 between pin 60 and pin 28 and the section 39 between the pin 28 and pivot pin 50 to drive the movable arm 25 in a clockwise direction about pin 50.

Since the closing pivot is pin 50, the magnetic forces on opposite sides of pin 50 on sections 39 and 41 of arm 25 at least cancel each other out so that the mechanical closing force meets no opposition. With section 39 of arm 25 even slightly greater than the distance from pivot 50 to contact 26, a net blow-closed action occurs.

As soon, however, as the toggle 52 is broken by the disengagement of the latch 64 from pin 63 in response to the fault currents as described above, the pin 50 ceases to be fixed as on pivot point for the movable arm 25 and the pivot point for the movable arm now is transferred to the pin 60 as described above.

Accordingly a blow-open action on the movable arm 25 is produced extending over the entire length of the arm 25 from the engaging contacts to the pin 60, thus ensuring high speed disengagement of the contacts.

In Figures 4 to 6, I have shown a modified form of circuit breaker which may be employed in my novel system. In this system, a circuit breaker 110 is shown arranged so that during the closing movement and just as the contacts engage, but before they have fully engaged, the current loop through the elements provides a blow-closed effect. When the circuit breaker is tripped, the elements are so arranged that the current loop provides a blow-open effect and the contacts are of the blow-closed construction.

The circuit breaker 110 is supported in any suitable manner on a panel 111, carrying the additional supporting bracket 112 and front panel 113.

The back panel 111 carries an upper back connection stud 215 and a lower back connection stud 216, mounted in any suitable insulator 115 and 116. The upper back connection stud 215 carries at the end thereof a stationary contact housing 117 comprising an arcing contact 118 and a main stationary contact 119. The arcing and main contacts 118 and 119 are supported in any suitable manner in the contact housing 117 and are biased toward current carrying relation with the movable contact elements by the compression springs 120, 121. They are so arranged in any of the well-known methods so

that the electromagnetic force due to high short circuit current will tend to force them into better contact engagement with the moving contact.

The movable contact arm 125 is a composite linkage member having an upper arm 126 and a lower arm 127 connected by the pin 128. The lower arm 127 is rotatably mounted on the stud 130 connected to the extension 131 of the lower back connection stud 216 and is held in current carrying engagement therewith by the friction discs 133. The lower arm 127 is held in current carrying engagement with the upper arm 126 also by friction discs 135 surrounding the pin 128.

Upper arm 126 has an angular extension 140 therefrom substantially in the region of the pin 128, the said extension 140 having secured to the outer end thereof at the pin 141 the upper end of the tension spring 142 which tends to bias the upper arm 126 toward the open position. The lower end of tension spring 142 is secured to the lower pin 130. The upper arm 126 carries the movable arcing contact 145 and the movable main contact 146.

The current path established when the contacts are closed is thus from the upper back connection stud 215 to the stationary contact structure 117, including the arcing contact 118 and the main contact 119, then through the movable arcing contact 145 and the movable main contact 146 to the upper arm 126 of the contact arm 125, then through the friction discs 135 and pin 128 to the lower arm 127 of the composite contact arm 125, then through the friction discs 133 and pin 130 to the extension 131 of lower back connection stud 216.

It will thus be seen that when the contacts are closed, a U-shaped current loop is established with the contact elements 118—145 and 119—146 at one of the bends or corners of the loop.

Accordingly, were it not for the specific novel structure of the contact arm 125, a blow-open effect would be seen to result on the contacts when the breaker is in the closed position.

Actually, the contact arm 125 and its associated operating mechanism is so designed that a blow-closed effect results. This occurs primarily by reason of the fact that the distance from the pin 150 to the pin 130 is greater than the distance from pin 150 to the contacts 146 and 145, and the flexible stationary contacts are of a blow-closed design.

The effect of this difference in length or distance will be obvious from a fuller explanation of the operating mechanism itself and the manner in which it co-acts with the contact arm 125.

The upper arm 126 of the contact arm 125 is biased toward opening position by the tension spring 142 in the manner previously described, the tension spring 142 causing the arm 126 and its extension 140 to rotate in a clockwise direction when the force which holds the contact arm 126 closed is removed.

Contact arm 126 is held in the closed position by the toggle 152 comprising links 153 and 154 and the knee pin 155. Link 153 may be of insulating material in some cases. Link 153 is pivotally connected to pin 150 of upper arm 126 and at its opposite end is connected to knee pin 155. Link 154 is connected at one end to pin 155 and at its opposite end is pivoted on the pin 157 mounted between the sides of bracket 160 which in turn is supported on the front panel 113.

Link 154 has an angular extension 162 so that members 154—162 form a bell crank lever around

the pin 157. The outer or lower end of extension 162 carries a latch roller 163 which is engaged by the latching detent 164 of the pivoted latch member 165. Latch member 165 is rotatably mounted on the pin 166 carried between the sides of bracket 160.

The latch lever 165 is in the path of movement of the armature 170 of trip coil 171. Armature 170 is connected to the short time delay device 172 and through spring 173 to the long time delay device 175 of the type shown more fully in Patent 2,439,165. As explained hereinbefore, and also in the above-identified patent, the armature is delayed in its operation for relatively long periods of time of the order of seconds when overload current conditions obtain in the main circuit being protected and is delayed in its operation for relatively short periods of time of the order of cycles when short circuit currents obtain in the main circuit being protected.

When the trip coil 171 is energized in response to predetermined circuit conditions, the armature 170 rotates the latch member 165 in counterclockwise direction to release the latching detent 164 of the latch 165 from the latch roller 163 of the bell crank lever 154—162.

Since the toggle 153—155—154 is broken slightly upwardly in the closed position of the circuit breaker, the arm 126 may now on release of the latch roller 163 rotate clockwise around the pin 128 breaking the toggle 152 up to the position shown in Figure 5. This movement of the arm 126 in a clockwise direction is in response to the force of the tension spring 142 which therefore acts as the opening spring of the circuit breaker. During this opening stroke of the breaker, it will be noted that the effect of the electromagnetic forces due to current flowing in the circuit is to hasten the contact opening, thus aiding high speed circuit interruption. This I have called the "blow-open" effect.

A portion of the link 154 strikes the buffer 174 carried by the front panel 113 and the upward breaking of the toggle 152 and hence the opening movement of contact arm 126 is thereby limited.

The closing arm 180 which may be of insulating material is connected at one end to the pin 128 and at the opposite end to a pin 181 on the armature 182 of the closing solenoid 183. The armature 182 is normally biased toward the left by the compression spring 185 which is seated at one end in the recess 186 of armature 182 and at the opposite end in the recess 187 of the housing 188 for the coil 183. Housing 188 is supported from the front panel 113.

With the circuit breaker in the open position, the compression spring 185 as seen in Figure 6 has moved the armature 182 fully to the left, thus moving the closing arm 180 and the pin 128 to the left and rotating the lower arm 127 of the contact arm 125 counterclockwise around the pin 130.

In the fully closed position of the circuit breaker, (Figure 4) the energization of the closing coil 183 has attracted the armature 182 to the right compressing the spring 185 and pulling the arm 180 and pin 128 to the right and rotating the lower arm 127 of contact arm 125 clockwise around the pin 130. When the closing movement is completed, the arm 180 is latched in closed position as shown in Figure 4 by the latch roller 190 in the latching detent 191 of the arm 180.

To ensure this movement and to limit the movement of arm 126 during opening, a pro-

jection 184 on closing arm 180 is arranged to engage arm 126 in the fully open position and drive it clockwise to the reset position of Figure 6.

Latch roller 190 is supported at the end of the bell crank latching lever 192, which latching lever is rotatably supported on the pin 193 carried by an extension 194 of bracket 160. The upper arm 195 of latching lever 192 is so arranged that during the opening movement of the circuit breaker, that is, when the circuit breaker moves from the position of Figure 4 to the position of Figure 5, the latch roller 163 at the end of arm 154—162 will strike the upper end 195 of the latching lever 192, as seen in Figure 5, to rotate the latching lever 192 counterclockwise and to move the latch roller 190 out of the latching detent 191 of closing arm 180 so that the closing arm 180 may move to the left in response to the bias of compression spring 185.

Tension spring 196 connected between the arm 195 of the latching lever 192 and extension 197 of the latching lever 165 biases the latching lever 192 toward clockwise rotation and hence toward latching position with respect to arm 180, and at the same time biases the latching lever 165 toward clockwise rotation and interengagement with the latch roller 163. The single spring 196 is thus used to re-set both of the latching levers 165 and 192.

Thus, as previously described, on a tripping of the circuit breaker, the armature 170 rotates latch lever 165 counterclockwise to release the latch roller 163 and to permit the toggle 152 to break upwardly so that the arm 126 may rotate clockwise toward opening position in response to the bias of spring 142. This is the initial step which occurs during tripping and is shown in Figure 5.

As the toggle 152 breaks upwardly, roller 163 strikes the upper arm 195 of the latching lever 192, rotating the latching lever 192 counterclockwise and lifting the latch roller 190 out of the latching detent 191. The arm 180 is now free to move in response to the bias of the compression spring 185 and moves to the left carrying the pin 128 with it and rotating the lower arm 127 of the contact arm 125 counterclockwise. This moves the lower end of arm 126 to the left taking with it the pin 150 and the link 153.

The latch roller 190 of the latch member 192 rides on the upper surface of the closing arm 180 as shown in Figure 6. Latches are thus reset preparatory to closing the breaker.

The re-set of this mechanism brings the movable contacts 145 and 146 nearer the stationary contacts 118—119 than they were in the tripped position (Figure 5) and thus reduces the travel required to close them.

In the closing operation, the energization of the closing coil 183 attracts the armature 182 to the right against the bias of compression spring 185 pulling the arm 180 to the right and hence rocking the pin 128 and the lower arm 127 clockwise about pivot 130. This same movement of pin 128 will rock the upper arm 126 counterclockwise about pin 150 since the pin 150, except for a slight upward movement to allow for the arc formed by pin 128 in its clockwise movement, is now substantially a fixed pivot owing to the fact that the toggle 152 is restrained from breaking upwardly by engagement of latch elements 163 and 164.

Accordingly, the upper arm 126 now rotates counterclockwise around the pin 150 as the arm 180 is drawn to the right and as the elements

move from the position of Figure 6 to the closed position of Figure 4. When the fully closed position is reached, the latch roller 190 drops into the latching detent 191 of the closing arm 180 and the circuit breaker is latched closed.

Examining the first operation of closing the circuit breaker, that is, the movement of the elements between the positions of Figures 6 and 4, it will be seen that movement of the arm 180 to the right rotates lower arm 127 clockwise around its pivot 130 and the upper arm 126 counterclockwise around its pivot 150 until the arms (which rotate with respect to each other about the pins 128) are substantially straight and the circuit breaker contacts engage.

The magnetic forces induced by current in the loop from back connection stud 215 through contacts 119, 146, arm 125 and lower stud 216 tends to rock arm 127 about pivot 130 in a clockwise direction. This force is transmitted through pin 128 to the arm 126 as a force tending to rock arm 126 about pin 150 in a counterclockwise direction. A second effect of the electromagnetic force is to directly apply a moment of rotation against the lower portion of arm 126 from pin 150 to pin 128 which tends to drive arm 126 in a counterclockwise direction. These two moments, the moment of rotation transferred through arm 127, and that directly applied to the lower part of arm 126, are accumulative and counterclockwise.

A third moment of rotation is applied by the integrated force due to the electromagnetic action of the upper part of arm 126 from pivot 150 to contact 119. This moment of rotation tends to rotate the arm 126 in a clockwise direction. It will be obvious from an examination of the proportional lengths of the arms involved that the sum of the movements about pin 150 in a counterclockwise direction are greater than the moment of rotation about pin 150 in a clockwise direction so that the resultant moment is one which drives the contacts into firmer engagement while the contacts are closed. This is called a "blow-closed" effect. An analysis of these forces is shown in Figure 4a.

The condition for equilibrium where all forces will be balanced out and no force will be imposed on the closing link 180 is

$$F_1d_1 = F_2d_2 + F_3 \frac{d_3d_5}{d_4}$$

If, however,

$$F_1d_1 < F_2d_2 + F_3 \frac{d_3d_5}{d_4}$$

then the electromagnetic forces due to current flowing in the circuit will help close the contacts and high speed positive closing will be secured due to this "blow closed" effect.

This current loop, as previously pointed out, will be established just as the contacts engage, but before they are in full engagement and hence before the latch roller 190 is forced by the spring 196 into latching detent 191.

With armature 182 at the end of its stroke at about this time, the net blow-closed effect achieved assists the closing coil 183 in completing the closing action. The contacts are forced home by this net blow-closed effect until the latch roller 190 enters the latching detent 191 when the contacts are secured in position.

Accordingly, the closing coil 183 and armature 182 need only have sufficient force to extend the tension spring 142 and move the mechanical

parts associated with the contact. They need not be designed to overcome any blow-open effect.

In fact, the closing coil and armature, as above pointed out, are aided by the arrangement of the parts which produce a net blow-closed effect during closing.

Also, the travel which is given to the closing coil and armature 182 need merely be sufficient to complete the closing operation and no overtravel need be provided to provide any hammer blow or kinetic effect to slam the contacts home. The parts may thus be made lighter and at the same time, owing to the utilization of the electromagnetic forces to close the contacts rather than sheer mechanical force or kinetic energy, the parts are more durable.

My novel device is also so arranged, however, that during the opening of the circuit breaker, a net blow-open effect is achieved. As will be seen from a comparison of Figures 4 and 5, when the circuit breaker is tripped, the toggle 152 first breaks upwardly and the contact arm 126 rotates clockwise in response to the tension of tension spring 42; and it is only after the toggle 152 has broken upwardly that its roller 163 can release the latch 192 to permit the arm 180 to move.

Consequently, at the instant of tripping, the pin 128 is effectively a stationary pin. Accordingly, during opening arm 126 rotates about at 128 in a clockwise direction. The magnetic forces set up a moment of rotation which is an integrated force between pin 128 and contact 115 multiplied by half the distance between the points. This moment of rotation is also clockwise and drives the contacts open. This is the blow-open effect.

Accordingly, the blow-open effect at the bend or corner of the U at which the contacts are located can exercise its full force and the tripping operation initiated by the opening spring 142 is substantially aided by the blow-open effect.

By this means, therefore, the single composite contact arm 125 is so arranged that it utilizes the electromagnetic forces of high fault currents to assist in closing the circuit breaker where the circuit breaker is to be closed on such high fault currents, and also utilizes the same electro- and magnetomotive effects of the high fault currents to speed up the tripping of the circuit breaker when the tripping operation occurs.

The same contact arm 125 is thereby utilized as a blow-closed contact arm during the closing operation of the circuit breaker and a blow-open contact arm during a tripping operation of the circuit breaker.

I claim:

1. Tripping mechanism for a circuit breaker having a movable contact carrying arm and a cooperating contact, a first and second pivot for said movable arm, electromagnetic means for controlling said movable arm about said first pivot to effect disengagement of said contacts, a long time delay mechanism for varying the controlling action of said electromagnetic means in the event that said electromagnetic means is energized by overload conditions to effect a delay in the disengagement of said contacts for a relatively long time of the order of seconds, a short time delay means for varying the controlling action of said electromagnetic means in the event said electromagnetic means is energized by short circuit fault currents to ef-

fect a delay in the disengagement of said contacts for a relatively short period of time of the order of cycles, and means operating said movable arm about said second pivot to effect engagement of said contacts.

2. Tripping mechanism for a circuit breaker having a movable contact carrying arm and a cooperating contact, a first and second pivot for said movable arm, a spring biasing said movable arm to disengaged position, a latch for normally latching said movable arm in contact engagement against the action of said spring electromagnetic means for tripping said latch to permit movement of said movable arm about said first pivot to disengage said contacts, a long time delay mechanism in operative relation with said electromagnetic means for varying the trip time of said latch a long time of the order of seconds in the event that said electromagnetic means is energized by predetermined overload current conditions and a short time delay means in operative relation with said electromagnetic means for varying the trip time of said latch a short time of the order of cycles when said electromagnetic means is energized by short circuit fault, and means operating said movable arm about said second pivot to effect engagement of said contacts.

3. In a circuit interrupter for connection in an electric circuit, a movable arm carrying a contact, a cooperating contact, means for operating said movable arm to effect engagement between the contact carried thereby and said cooperating contact, a first pivot, said movable arm being mounted on said pivot for movement about said pivot, the distance from said pivot to the contact carried on said movable arm being less than the distance from said pivot to the end of said arm opposite said contact carried by said arm, said arm and its contact and cooperating contact forming with the electric circuit in which said interrupter is connected a loop circuit, means for operating said movable arm about said first pivot to effect engagement of said contacts, a second pivot, electromagnetic means responsive to the electrical conditions in said circuit, means controlled by said electromagnet for operating said movable arm about said second pivot for effecting disengagement of said contacts, time delay mechanism associated with said last mentioned means for effecting delay in the disengagement of said contacts.

4. In a circuit interrupter for connection in an electric circuit, a movable arm carrying a contact, a cooperating contact, means for operating said movable arm to effect engagement between the contact carried thereby and said cooperating contact, a first pivot, said movable arm being mounted on said pivot for movement about said pivot, the distance from said pivot to the contact carried on said movable arm being less than the distance from said pivot to the end of said arm opposite said contact carried by said arm, said arm and its contact and cooperating contact forming with the electric circuit in which said interrupter is to be connected a loop circuit, means for operating said movable arm about said first pivot to effect engagement of said contacts, a second pivot, electromagnetic means responsive to the electrical conditions in said circuit, means controlled by said electromagnet for operating said movable arm about said second pivot for effecting disengagement of said contacts, time delay mechanism associated with said last mentioned means for effecting de-

lay in the disengagement of said contacts, said delay being of the order of seconds for predetermined currents and of the order of cycles for predetermined currents of greater amplitude than said first mentioned predetermined currents.

5. In a circuit interrupter for connection in an electric circuit, a movable arm carrying a contact, a cooperating contact, means for operating said movable arm to effect engagement between the contact carried thereby and said cooperating contact, a first pivot, said movable arm being mounted on said pivot for movement about said pivot, the distance from said pivot to the contact carried on said movable arm being less than the distance from said pivot to the end of said arm opposite said contact carried by said arm, said arm and its contact and cooperating contact forming with the electric circuit in which said interrupter is connected a loop circuit, means for operating said movable arm about said first pivot to effect engagement of said contacts, a second pivot, the distance from said second pivot to the nearest turn in said loop being less than from said second pivot to said cooperating contact, electromagnetic means responsive to the electrical conditions in said circuit, means controlled by said electromagnet for operating said movable arm about said second pivot for effecting disengagement of said contacts, time delay mechanism associated with said last mentioned means for effecting delay in the disengagement of said contacts, said delay being of the order of seconds for predetermined currents and of the order of cycles for predetermined currents of greater amplitude than said first mentioned predetermined currents.

6. A circuit breaker for protecting an electrical circuit having terminals for connection to a circuit to be protected and having a pair of cooperable contacts, a contact carrying arm for carrying one of said cooperable contacts into and out of engagement with the other of said cooperable contacts, a closing mechanism connected to said contact carrying arm mechanism, a first latch for said closing mechanism operable after said cooperable contacts have been moved to engagement and then moved further to tight contact engagement for latching said contacts into tight engagement, a second latch for said movable contact carrying arm, a trip mechanism responsive to fault currents for releasing said second latch to permit movement of said contact carrying arm to effect disengagement of said contacts, a time delay for retarding the time of operation of said trip mechanism, said cooperable contacts forming with said movable contact carrying arm and said terminals a loop electrical circuit setting up electromagnetic forces applied to said movable contact carrying arm, and a construction for said movable contact carrying arm for applying said electromagnetic forces to said arm in a direction to assist said closing mechanism in effecting contact engagement of said cooperable contacts until said first latch is operated and for applying said electromagnetic forces to said arm in a direction to drive said contacts apart after said first latch is operated.

7. A circuit breaker for protecting an electrical circuit having terminals for connection to a circuit to be protected and having a pair of cooperable contacts, a contact carrying arm for carrying one of said cooperable contacts into and out of engagement with the other of said cooper-

able contacts, a closing mechanism connected to said contact carrying arm mechanism, a first latch for said closing mechanism operable after said cooperable contacts have been moved to engagement and then moved further to tight contact engagement for latching said contacts into tight engagement, a second latch for said movable contact carrying arm, a trip mechanism responsive to fault currents for releasing said second latch to permit movement of said contact carrying arm to effect disengagement of said contacts, a time delay for retarding the time of operation of said trip mechanism, said cooperable contacts forming with said movable contact carrying arm and said terminals a loop electrical circuit setting up electromagnetic forces applied to said movable contact carrying arm, and a construction for said movable contact carrying arm for applying said electromagnetic forces to said arm in a direction to assist said closing mechanism in effecting contact engagement of said cooperable contacts until said first latch is operated and for applying said electromagnetic forces to said arm in a direction to drive said contacts apart after said first latch is operated, said construction of said arm comprising a first pivotal connection from said arm to said closing mechanism latch and a second pivotal connection to said second latch, the distance from said second pivotal connection to said cooperable contacts being less than the distance from said second pivotal connection to the terminal connection of said arm.

9. A circuit breaker for protecting an electrical circuit having terminals for connection to a circuit to be protected and having a pair of cooperable contacts, a contact carrying arm for carrying one of said cooperable contacts into and out of engagement with the other of said cooper-

to said contact carrying arm mechanism, a first latch for said closing mechanism operable after said cooperable contacts have been moved to engagement and then moved further to tight contact engagement for latching said contacts into tight engagement, a second latch for said movable contact carrying arm, a trip mechanism responsive to fault currents for releasing said second latch to permit movement of said contact carrying arm to effect disengagement of said contacts, a time delay for retarding the time of operation of said trip mechanism, said cooperable contacts forming with said movable contact carrying arm and said terminals a loop electrical circuit setting up electromagnetic forces applied to said movable contact carrying arm, and a construction for said movable contact carrying arm for applying said electromagnetic forces to said arm in a direction to assist said closing mechanism in effecting contact engagement of said cooperable contacts until said first latch is operated and for applying said electromagnetic forces to said arm in a direction to drive said
